ABSTRACT

A snubbing plug containing a body and a piston is config-
ured to be secured within a component of a mineral extrac-
tion system by an internal locking mechanism. A fluid
passage extends at least partially through the piston of the
snubbing plug. The snubbing plug is configured to selec-
tively open the fluid passage during installation or removal
of the snubbing plug.

INTERNAL LOCKDOWN SNUBBING PLUG

CROSS REFERENCE TO RELATED APPLICATIONS

This application claims priority to and benefit of U.S. Non-provisional application Ser. No. 14/216,465, now U.S. Pat. No. 9,255,460, issued on Feb. 9, 2016, entitled "Internal Lockdown Snubbing Plug," filed on Mar. 17, 2014, which is herein incorporated by reference in its entirety, and which claims priority to and benefit of U.S. Non-provisional application Ser. No. 12/920,823, now U.S. Pat. No. 8,701,756, issued on Apr. 22, 2014, entitled "Internal Lockdown Snubbing Plug," filed on Sep. 2, 2010, which is herein incorporated by reference in its entirety, and which claims priority to and benefit of PCT Patent Application No. PCT/US09/35166, entitled "Internal Lockdown Snubbing Plug," filed on Feb. 25, 2009, which is herein incorporated by reference in its entirety, and which claims priority to and benefit of U.S. Provisional Patent Application No. 61/039,391, entitled "Internal Lockdown Snubbing Plug," filed on Mar. 25, 2008, which is herein incorporated by reference in its entirety.

BACKGROUND

This section is intended to introduce the reader to various aspects of art that may be related to various aspects of the present invention, which are described and/or claimed below. This discussion is believed to be helpful in providing the reader with background information to facilitate a better understanding of the various aspects of the present invention. Accordingly, it should be understood that these statements are to be read in this light, and not as admissions of prior art.

Natural resources, such as oil and gas, are used as fuel to power vehicles, heat homes, and generate electricity, in addition to a myriad of other uses. Once a desired resource is discovered below the surface of the earth, drilling and production systems are often employed to access and extract the resource. These systems may be located onshore or offshore depending on the location of a desired resource. Further, such systems generally include a wellhead assembly through which the resource is extracted. These wellhead assemblies may include a wide variety of components and/or conduits, such as casings, trees, manifolds, and the like, that facilitate drilling and/or extraction operations.

In some instances, well intervention, or any work involving maintenance, modification, repair, or completion of the well, may be performed by first killing the well and then removing pressure control equipment to enable pipes and/or tools to be lowered into the well. Well kill involves adding heavy fluid to a wellbore to provide hydrostatic pressure, thereby preventing the flow of reservoir fluids from the well. The heavy fluid provides enough pressure to overcome the pressure of the reservoir fluids such that pressure control equipment may be removed from the wellhead assembly to enable completion of the desired intervention. The heavy fluid introduced into the wellbore may impair the resumption of fluid flow after completion of the well intervention. Accordingly, in order to resume production after killing the well, the added heavy fluid is removed from the wellbore.

As an alternative to killing the well to enable intervention work, a technique known as snubbing may be employed while the well is under pressure. In snubbing, a plug is inserted into the well, for example, in the tubing spool. Pressure is thereby isolated upstream of the plug (e.g., between the plug and a mineral deposit, or below the plug),

and repairs or modifications may be made to well components downstream of the plug (e.g., between the plug and a riser, or above the plug). When the well intervention is complete, the snubbing plug may be removed and well operations may proceed as usual.

BRIEF DESCRIPTION OF THE DRAWINGS

Various features, aspects, and advantages of the present invention will become better understood when the following detailed description is read with reference to the accompanying figure, wherein:

FIG. 1 is a block diagram of a mineral extraction system in accordance with embodiments of the present invention;

FIG. 2 is a partial cross-section of an exemplary snubbing plug that may be used in the mineral extraction system illustrated in FIG. 1;

FIG. 3 is a partial cross-section of a component of the snubbing plug illustrated in FIG. 2; and

FIG. 4 is a partial cross-section of the exemplary snubbing plug illustrated in FIG. 2 in a pressure equalization running position;

FIG. 5 is a partial cross-section of the exemplary snubbing plug illustrated in FIG. 2 in a pressure isolation position;

FIG. 6 is a partial cross-section of the exemplary snubbing plug illustrated in FIG. 2 in a pressure equalization retrieval position;

FIG. 7 is a partial cross-section of another exemplary snubbing plug that may be used in the mineral extraction system illustrated in FIG. 1.

DETAILED DESCRIPTION OF SPECIFIC EMBODIMENTS

One or more specific embodiments of the present invention will be described below. These described embodiments are only exemplary of the present invention. Additionally, in an effort to provide a concise description of these exemplary embodiments, all features of an actual implementation may not be described in the specification. It should be appreciated that in the development of any such actual implementation, as in any engineering or design project, numerous implementation-specific decisions must be made to achieve the developers' specific goals, such as compliance with system-related and business-related constraints, which may vary from one implementation to another. Moreover, it should be appreciated that such a development effort might be complex and time consuming, but would nevertheless be a routine undertaking of design, fabrication, and manufacture for those of ordinary skill having the benefit of this disclosure.

When introducing elements of various embodiments of the present invention, the articles "a," "an," "the," and "said" are intended to mean that there are one or more of the elements. The terms "comprising," "including," and "having" are intended to be inclusive and mean that there may be additional elements other than the listed elements. Moreover, the use of "top," "bottom," "above," "below," and variations of these terms is made for convenience, but does not require any particular orientation of the components.

As discussed further below, snubbing operations may be conducted while the well is under pressure. A securing device holds the snubbing plug in place during the course of well intervention. One or more external fasteners, such as tie-down pins, may be used as the securing device for holding the snubbing plug within the wellhead component. The tie-down pins function by protruding radially through

the walls of the wellhead component and holding the snubbing plug in place (i.e., preventing the snubbing plug from axial movement with respect to the wellhead component). Upon advancement of the tie-down pins into the wellhead component, a compression seal disposed between the snubbing plug and the wellhead component is compressed such that pressure may not be transferred between the snubbing plug and the wellhead component. Unfortunately, because the tie-down pins protrude through the walls of the wellhead component, they must be secured via an external force. For example, the tie-down pins may be large screws which are advanced into the wellhead via rotational movement applied to a portion of the tie-down pins which protrudes from the exterior of the wellhead. This rotational force operates to advance the tie-down pins in a generally radial direction into the wellhead component (e.g., transverse to an axis of the wellhead component), and must be applied at the location of the snubbing plug. That is, wherever the snubbing plug is disposed within the wellhead component, tie-down pins protruding from the wellhead at that location must be screwed in to secure the snubbing plug in place within the wellhead component.

In contrast, in embodiments described below, the securing device includes an internal lockdown mechanism (e.g., an inner locking ring, a threading, etc.). By securing the snubbing plug to the wellhead component internally (i.e., via a mechanism disposed entirely within the wellhead component), the need for an external fastener is eliminated, and installation of the snubbing plug is greatly simplified. In certain embodiments, the disclosed snubbing plug may include a mount consisting essentially of an internal lockdown mechanism (i.e., a lockdown mechanism internal to the wellhead component in which the snubbing plug is installed). The disclosed snubbing plug may also be described as excluding external mounts in certain embodiments. That is, there may be no fasteners or other securing mechanisms external to the wellhead component which mount the snubbing plug within the component. Moreover, this lack of external penetrations reduces the potential for leakage or integrity-related failure.

In addition, one or more fluid pathways through the snubbing plug enable pressure to be equalized above and below the plug during insertion of the plug within the wellhead. After the well intervention is complete, the snubbing plug may be removed. However, due to the difference in pressure above and below the plug, the plug and its associated tool and rod may be rapidly ejected upon release of the snubbing plug. Accordingly, in embodiments discussed below, a pressure equilibration mechanism may be incorporated into the snubbing plug to equalize pressure above and below the plug before the plug is unsecured from the wellhead. By providing a fluid path through the snubbing plug, the pressure equilibration mechanism may equalize pressure above and below the snubbing plug before the snubbing plug is removed from the wellhead.

FIG. 1 illustrates a mineral extraction system 10 equipped for snubbing operations in accordance with exemplary embodiments of the present technique. The mineral extraction system 10 may be configured to extract minerals, such as oil and gas, from a mineral deposit 12 beneath a surface 14. In various embodiments, the mineral deposit 12 may be located under the sea floor or under dry land.

The illustrated mineral extraction system 10 includes a wellhead 16 having a casing spool 18, a tubing spool 20, and a blowout preventer 22. The casing spool 18 houses a casing hanger 24 that supports a casing 26. Similarly, the tubing spool 20 has a tubing hanger 28 that supports a production

tubing 30. Multiple tubings may be disposed concentrically within the casing 26. The production tubing 30 may be utilized to transfer minerals from the mineral deposit 12 to the wellhead 16. Other tubings and/or the casing 26 may be utilized to transport various production fluids to and from the mineral deposit 12 or to isolate various regions of the formation, for instance.

In order to enable well intervention without killing the well, a snubbing plug 32 may be disposed above the tubing 10 hanger 28. The snubbing plug 32 may substantially seal the wellhead 16 during snubbing operations, while equilibrating pressure above and below the snubbing plug 32 before the plug 32 is removed from the wellhead 16. In the illustrated embodiment, the snubbing plug 32 is disposed below the blowout preventer 22 such that any unexpected pressure release from the well may be contained by the blowout preventer 22 so that minerals are not released into the environment. Additional valves and blowout preventers 22 also may be installed above the snubbing plug 32. Thus, one 15 or more blowout preventers 22 may be opened to enable running in and removal of the snubbing plug 32.

FIG. 2 is a partial cross-section of an exemplary snubbing plug 40 for use in the mineral extraction system illustrated in FIG. 1. The snubbing plug 40 generally includes a body 42, a load ring 44, and a piston 46. Protruding from the load ring 44 are one or more load pins 48 which correspond to one or more slots 50 in the body 42. The load ring 44 may rotate around and move along an axis 52 with respect to the body 42. Movement of the load ring 44 is limited by 25 engagement of the slots 50 with the load pins 48. FIG. 3 illustrates an exemplary configuration of the slot 50 in a cross-section of the body 42 through a line 3-3 (FIG. 2). As 30 illustrated in FIG. 3, the slot 50 may contain a plurality of circumferential paths 54 and 56 (e.g., paths that limit the pin 48 to movement about an inner circumference of the body 42) and a plurality of axial paths 58 and 60 (e.g., paths that limit the pin 48 to movement along the axis 52). Accordingly, the load ring 44 may only rotate to the degree that the 35 load pins 48 may travel circumferentially along the paths 54 and 56 (i.e., along arrows 62 and 64). Likewise, the load ring 44 may only move axially to the extent that the load pins 48 40 may move axially within the paths 58 and 60 (i.e., along arrows 66 and 68).

Referring again to FIG. 2, the piston 46 may also move 45 along the axis 52 in conjunction with the load ring 44. A bearing 70 between the load ring 44 and the piston 46 enables rotation of the load ring 44 with respect to the piston 46. This configuration enables fluid pathways through the 50 snubbing plug 40 to be opened and closed by simply rotating the load ring 44. That is, one or more bores 72 in the piston 46 may align with one or more bores 74 in the body 42 depending on the axial position of the piston 46, thereby 55 opening and/or closing fluid pathways through the snubbing plug 40. The load ring 44, the piston 46, the load pins 48, and the bearing 70 may be considered components of a valve which can be opened or closed to equalize or isolate fluid 60 pressure, respectively. In addition, the snubbing plug 40 may include a locking ring 76 to enable secure attachment of the plug 40 within the wellhead without external fasteners, as described in more detail below.

Turning to FIG. 4, the exemplary snubbing plug 40 is 65 illustrated in a pressure equalization running position 100 as it is landed in an exemplary tubing spool 102. However, the snubbing plug 40 may be utilized to provide a pressure seal in any wellhead component. In the illustrated embodiment, a blowout preventer 104 is disposed above and secured to the tubing spool 102 during snubbing operations. Any well-

head component may be situated above the snubbing plug 40 while it is installed in a wellhead component (e.g., the tubing spool 102). Moreover, the snubbing plug 40 can be employed to close a variety of annular regions, including the production casing, for example,

A running tool 106 may be secured to the snubbing plug 40, for example, via complimentary threads 108 and 110 on the running tool 106 and the snubbing plug 40, respectively. The running tool 106 may include a lip 112 which compresses the locking ring 76 while the running tool 106 advances the snubbing plug 40 into the tubing spool 102. Upon detachment or retraction of the running tool 106, the locking ring 76 may automatically expand radially into a locking recess 114 in the tubing spool 102. Complimentary shoulders 116 and 118 on the locking ring 76 and the locking recess 114, respectively, prevent the snubbing plug 40 from moving axially upward with respect to the tubing spool 102. That is, the shoulder 116 on the locking ring 76 may be pressed against the shoulder 118 on the locking recess 114, thereby blocking axial movement of the snubbing plug 40 with respect to the tubing spool 102. This internal locking mechanism enables installation of the snubbing plug 40 without external fasteners. That is, external fasteners are not advanced through an outer wall of the tubing spool 102 to secure the snubbing plug 40 within the tubing spool 102. The internal locking function, whether lock ring, threads, segment, or dogs, enables faster and easier installation of the snubbing plug 40, thereby reducing the costs associated with snubbing operations.

Turning back to FIG. 4, a shaft 120 provides a running guide for installation of the snubbing plug 40. In addition, a spring 122 may be disposed about the shaft 120 to apply axial load to the piston 46. That is, the spring 122 may be secured within the snubbing plug 40 by a hold down ring 124 and held in place by the shaft 120. The spring 122 provides a force which automatically biases the piston 46 away from the hold down ring 124 and towards the bearing 70, thereby enabling positioning of the piston 46 via adjustment of the load ring 44 when the wellbore has low or no pressure.

During advancement of the snubbing plug 40 into the tubing spool 102, pressure below the plug 40 may be released through the snubbing plug 40 via the bores 72 in the piston 46 and the bores 74 in the body 42. That is, a first opening 126 in the bore 72 is aligned with an opening 128 in the bore 74. One or more bores 130 in the hold down ring 124 enable flow of fluid pressure into the bores 72 in the piston 46. One or more radial seals 132 disposed about the body 42 may disable fluid from flowing between the snubbing plug 40 and the tubing spool 102 during installation of the plug 40.

After installation of the snubbing plug 40 in the tubing spool 102, the plug 40 may be moved into a pressure isolation position 150, as illustrated in FIG. 5. This conversion may be facilitated by a pressure tool 152. The pressure tool 152 and the running tool 106 (FIG. 3) may be one tool which performs multiple functions, or separate tools may be utilized for the various snubbing operations. In either embodiment, the lip 112 (FIG. 4) is axially retracted to enable the snubbing plug 40 to lock in place within the tubing spool 102.

The pressure tool 152 may be connected to the load ring 44 via a shaft 154 such that rotation of the shaft 154 rotates the load ring 44 with respect to the body 42. Referring again to FIG. 3, upon rotation of the load ring 44, the load pin 48 moves from a first position 156 along the circumferential pathway 54 to a second position 158 (e.g., in the direction

of the arrow 62). Due to upward force on the piston 46 (e.g., from fluid pressure below the snubbing plug 40 and/or applied force from the spring 122), the piston 46, the bearing 70, and the load ring 40 automatically move axially upward upon reaching the second position 158. The load pin 48 moves from the second position 158 to a third position 160 along the axial pathway 58 (e.g., in the direction of the arrow 66).

Turning back to FIG. 5, it can be seen that the fluid pathways through the snubbing plug 40 have been closed. That is, bores 72 are isolated from bores 74, and a plurality of elastomer seals 162 disposed between the piston 46 and the body 42 isolate the first opening 126 and the opening 128. The elastomer seals 162 further disable fluid pressure from escaping between the piston 46 and the body 42. As described above, the radial seals 132 block pressure transfer between the body 42 and the tubing spool 102. Accordingly, any pressure trapped below the snubbing plug 40 is isolated while the plug 40 is in the pressure isolation position 150. Snubbing operations may therefore be carried out while the well is sealed.

In certain embodiments, a mechanism 164 incorporated into the pressure tool 152 may prevent axial displacement of the tool 152 with respect to the snubbing plug 40 when the load ring 42 and the piston 46 are moved. That is, movement of the load ring 44 and the shaft 154 coupled thereto, due to pressure kickback from the well, may be absorbed by compression of a spring 166 within the pressure tool 152. This movement absorption mechanism 164 blocks axial movement within the snubbing plug 40 from being conveyed to the surface where users may be in proximity to the pressure tool 152.

After the snubbing operations have been completed, the snubbing plug 40 may be removed so that normal well operations may resume. Before the plug 40 is removed, it may be desirable to equalize pressure above and below the plug 40. This pressure equalization step may prevent the snubbing plug 40 from possibly being ejected when the plug 40 is no longer secured to the tubing spool 102. FIG. 6 illustrates the plug 40 in an exemplary pressure equalization retrieval position 180. As seen in FIG. 6, the bores 72 and 74 are again in fluid communication with each other. That is, a second opening 182 in the bore 72 is aligned with the opening 128 in the bore 74. This configuration enables fluid pressure to be conveyed through the snubbing plug 40 before the plug 40 is removed from the tubing spool 102.

The piston 46 is moved into the pressure equalization retrieval position 180 by another rotation of the load ring 44. As illustrated in FIG. 3, further rotation of the load ring 44 moves the load pin 48 from the third position 160 to a fourth position 184 along the circumferential path 56 (e.g., in the direction of the arrow 64). Again, once the pin 48 reaches the fourth position 184, an upward force on the piston 46 (e.g., from fluid pressure below the snubbing plug 40 and/or applied force from the spring 122) biases the load ring 44 axially upward. The load pin 48 is automatically moved from the fourth position 184 to a fifth position 186 along the axial pathway 60 (e.g., in the direction of the arrow 68). The pin 48 in the slot 50 blocks the load ring 44 from further axial movement. In addition, returning to FIG. 6, it can be seen that the load ring 44 and the piston 46 are prevented from further axial movement by a hold down ring 188.

After pressure equalization, the running tool 106 (FIG. 4) may again be secured to the snubbing plug 40. Advancement of the lip 112 compresses the locking ring 76 such that the shoulder 116 on the locking ring 76 may be moved past the

shoulder 118 on the locking recess 114, thereby enabling removal of the snubbing plug 40 from the tubing spool 102.

Another embodiment of a snubbing plug 200 is illustrated in FIG. 7. A load ring 202 and a piston 204 in the snubbing plug 200 operate similarly to those in the snubbing plug 40 to open and/or close fluid pathways through the plug 200. The snubbing plug 200 is illustrated secured to a tubing spool 206. However, the plug 200 may be installed in other mineral extraction equipment. In the embodiment illustrated in FIG. 7, complimentary threading 208 and 210 on the snubbing plug 200 and the tubing spool 206, respectively, enable secure attachment of the plug 200 to the spool 206. The snubbing plug 200 may be run into and secured to the tubing spool 206 via a running tool (not shown) coupled to the plug 200 by a "J" slot 212. That is, a connector on the running tool may correspond to the "J" slot 212 such that pressure and/or rotation of the tool engages and/or disengages the tool from the plug 200. In this embodiment, the snubbing plug 200 may be secured within the tubing spool 206 via rotation of the snubbing plug 200 with respect to the tubing spool 206, thereby engaging and securing the threads 208 and 210. While a rotational force may be applied to the snubbing plug 200 to implement the internal lockdown mechanism, this force may be applied from the running tool. This technique is therefore easier to implement than the presently-utilized tie-down pins which are generally employed to secure the snubbing plug within the tubing spool. As described with respect to the first embodiment illustrated in FIGS. 2-6, manipulation of the load ring 202 in the present embodiment may be accomplished via a pressure tool (not shown).

In view of the embodiments discussed above, the snubbing plug having an internal lockdown mechanism may be easily installed in a wellhead component below the ground surface or subsea. That is, because no external force is applied at the snubbing plug (i.e., tie-down pins are not advanced into the wellhead component to secure the snubbing plug in place), the plug may be installed entirely via the running tool. A one-trip installation may therefore be implemented which greatly reduces the time and cost of snubbing.

While the invention may be susceptible to various modifications and alternative forms, specific embodiments have been shown by way of example in the drawings and have been described in detail herein. However, it should be understood that the invention is not intended to be limited to the particular forms disclosed. Rather, the invention is to cover all modifications, equivalents, and alternatives falling within the spirit and scope of the invention as defined by the following appended claims.

The invention claimed is:

1. A system, comprising:
a plug, comprising:

a body;

a piston disposed in the body;

a fluid passage through the plug, wherein the fluid passage extends at least partially through the piston, and the plug is configured to selectively open the fluid passage during installation or removal of the plug in a bore of a mineral extraction system; and an internal lock configured to move between an unlocked position and a locked position within the bore of the mineral extraction system, wherein the piston is configured to move between a plurality of positions to open and close the fluid passage, and the fluid passage extends through the piston and the body.

2. The system of claim 1, wherein the plug comprises a snubbing plug.

3. The system of claim 2, comprising a blowout preventer configured to mount in the bore of the mineral extraction system, wherein the plug is configured to mount in the bore between the hanger and the blowout preventer.

4. The system of claim 1, comprising a hanger configured to mount in the bore of the mineral extraction system, wherein the plug is configured to mount in the bore above the hanger.

5. The system of claim 1, wherein the plug is configured to selectively open the fluid passage to enable pressure equalization above and below the plug in the bore of the mineral extraction system.

6. The system of claim 1, wherein the fluid passage comprises a first fluid passage and a second fluid passage, the plug is configured to selectively open the first fluid passage during installation of the plug into the bore, and the plug is configured to selectively open the second fluid passage during removal of the plug from the bore.

7. The system of claim 6, wherein the plug is configured to selectively move between a first position that opens the first fluid passage, a second position that closes the first fluid passage, and a third position that opens the second fluid passage.

8. The system of claim 7, wherein the piston is configured to selectively move between the first, second, and third positions via a sequence of movements along one or more axial paths and circumferential paths.

9. The system of claim 7, wherein the piston is configured to move within a body of the plug, and the internal lock is coupled to the body.

10. The system of claim 1, wherein the plurality of positions comprises at least three different positions.

11. The system of claim 1, wherein the fluid passage is offset from a central axis of the plug.

12. The system of claim 1, comprising a spring biasing the piston relative to the body of the plug.

13. The system of claim 1, wherein the fluid passage comprises a first axial passage in the piston, a first radial passage coupled to the first axial passage in the piston, and a second radial passage coupled to the first axial passage in the piston.

14. The system of claim 13, wherein the first and second radial passages are axially offset from one another.

15. The system of claim 14, wherein the fluid passage comprises a second axial passage in the body, and a third radial passage coupled to the second axial passage in the body.

16. The system of claim 1, wherein the internal lock comprises a radial lock configured to selectively move in a radial direction between the unlocked position and the locked position.

17. The system of claim 16, wherein the radial lock comprises a lock ring.

18. The system of claim 1, comprising a tubing having the bore and a radial passage coupled to the bore, wherein the plug is configured to mount in the bore at least partially above and below the radial passage.

19. A system, comprising:
a plug, comprising:
a body;
a piston;
a first fluid passage through the plug, wherein the first fluid passage comprises a first opening;
a second fluid passage through the plug, wherein the second fluid passage comprises a second opening,

the piston is configured to move along a path of travel between first and second positions relative to the body, the first position has the first opening of the first fluid passage open and the second opening of the second fluid passage closed, the second position has the first opening of the first fluid passage closed and the second opening of the second fluid passage open, and the first and second openings are offset from one another along the path of travel; and

an internal lock configured to move between an unlocked position and a locked position within the bore.

20. The system of claim 19, wherein piston is configured to selectively open the first or second fluid passage to enable pressure equalization above and below the plug in the bore.

21. A method, comprising:

equalizing pressure above and below a plug via a fluid passage through the plug during installation or removal of the plug in a bore of a mineral extraction system, wherein the plug has a piston disposed in a body, wherein the fluid passage comprises a first axial passage in the piston, a first radial passage coupled to the first axial passage in the piston, a second radial passage coupled to the first axial passage in the piston, and a third radial passage in the body of the plug, the piston has first and second seals configured to seal against the body, the piston is configured to move between first and second positions relative to the body, the third radial passage is open in the first position of the piston when

equalizing pressure, and the third radial passage is closed and sealed by the first and second seals in the second position of the piston when not equalizing pressure; and

internally locking the plug in the bore via an internal lock that moves between an unlocked position and a locked position relative to the bore.

22. The method of claim 21, comprising performing a snubbing operation while the plug is in the locked position in the bore and the fluid passage is closed, wherein the plug comprises a snubbing plug.

23. The method of claim 21, wherein internally locking comprises internally locking the plug above a hanger in the bore.

24. A system, comprising:

a plug configured to mount within a bore of a mineral extraction system, wherein the plug comprises:

a body;

a piston disposed in the body;

a fluid passage through the plug, wherein the piston is configured to move between a plurality of positions to selectively open and close the fluid passage, and the plurality of positions comprises at least three different positions; and

an internal lock configured to move between an unlocked position and a locked position within the bore.
